UNITED STATES PATENT OFFICE.

JAMES A. HINSON, OF CHICAGO, ILLINOIS; MARGARET HINSON, ADMINISTRATRIX OF SAID JAMES A. HINSON, DECEASED, ASSIGNOR TO NATIONAL CAR COUPLER COMPANY, OF CHICAGO, ILLINOIS, A CORPORATION OF ILLINOIS.

EMERGENCY ATTACHMENT FOR AUTOMATIC CAR-COUPINGS.

No. 820,644.

Specification of Letters Patent.

Patented May 15, 1906.

Application filed August 19, 1903. Serial No. 169,995.

To all whom it may concern:

Be it known that I, JAMES A. HINSON, of Chicago, in the county of Cook and State of Illinois, have invented certain new and useful 5 Improvements in Emergency Attachments for Automatic Car-Couplers; and I do hereby declare that the following is a full, clear, and exact description thereof, reference being had to the accompanying drawings, and to the 10 letters of reference marked thereon, which form a part of this specification.

This invention relates to improvements in railway-car couplers, and refers more specifically to a novel device in the nature of an 15 emergency attachment which is adapted to take the place of a broken or disabled knuckle and so constructed as to be coupled to any of the standard couplers of the vertical-plane type or couplers having the general form and 20 construction of such type.

The invention consists in the matters hereinafter described and set forth, and more particularly pointed out in the appended claims.

In the drawings, Figure 1 is a plan view of 25 two couplers connected or coupled by means of my improved coupling attachment. Fig. 2 is a side elevation of a coupler-head and my attachment connected therewith. Fig. 3 is a plan view of the parts shown in Fig. 1, the 30 parts being in the position which they assume when approaching each other preparatory to coupling. Fig. 4 is an end elevation of the parts shown in Fig. 2. Fig. 5 is a plan view of two couplers connected by a modified 35 form of my attachment. Fig. 6 is a side view of the construction shown in Fig. 5 with portions broken away.

First referring to the construction shown in Figs. 1 to 4, A B designate the draw-heads 40 of two couplers of the Master Car-Builders' type. The knuckle of the coupler A is assumed to have been disabled, while the knuckle B' of the coupler B occupies its usual position in the draw-head, being hinged thereto in the usual manner. My novel emergency attachment is designed to be hinged to the draw-head A, which is minus its knuckle, and is constructed to be hinged between the jaws or lugs a, which in the complete coupler 45 receives the usual knuckle, to which it is hinged by means of the usual pivot-pin a'.

Referring now to the form of the device or attachment shown in Figs. 1 to 4, said device consists, essentially, of a link (designated as a whole by the letter C) which is provided at 55 one side with a swinging knuckle C' and at its other side with a laterally-projecting guard-arm C², the parts being constructed to inter-couple with the swinging knuckle B' and guard-arm B² of the fully-equipped coupler. 60 The rear end of said link is reduced to fit between the jaws or lugs a of the draw-head A, and said reduced part is vertically apertured to receive the hinge-pin a' before mentioned. The forward end of the link C is recessed or 65 cut away to form upper and lower jaws c c, and the knuckle is reduced at c' to fit between said jaws, and said knuckle is hinged to the link by means of a hinge-pin c², which extends through registering apertures in said 70 jaws and the reduced portion of the knuckle. Said knuckle is provided with a rearwardly-directed tailpiece C³, which when the knuckle is closed, occupies a cored-out recess c³ in the link. (Shown partially in full lines in Fig. 2 75 and in dotted lines in Figs. 1 and 3.) The link is provided in said cored-out portion with a vertical aperture c⁴, and the tailpiece C³ of the knuckle is provided with an aperture c⁵, which registers therewith when the knuckle is 80 closed, and said knuckle is locked closed by means of a lock-pin C⁴, which extends through the said registering apertures c⁴ c⁵. The tailpiece is provided with an extension C⁵, which when the knuckle is wholly open extends partially across the lock-bolt aperture c⁴ of the 85 link, so as to support the lock-pin C⁴ in its raised or set position, and when the knuckle is swung closed the pin rides on said extension and the tailpiece until the aperture c⁵ of 90 said tailpiece registers with the lock-pin aperture of the link, whereupon the lock-pin drops into its locking position and automatically locks the knuckle closed. The knuckle C is provided with a stop-shoulder c⁶, which is 95 adapted to strike a stop-surface on the link to limit the opening movement of the knuckle. The guard-arm C² is provided on its forward or inner surface with a rearwardly-curved notch or recess c⁸, which is so located as to allow the knuckle B' of the coupler B to pass 100 freely into and out of the space between said

- guard-arm and the knuckle C' during coupling and uncoupling, and thereby prevent the end of said knuckle B' binding against said link guard-arm during such movements.
- 5 The forward end of said link is provided with a curved projection c⁹, adapted for engagement with the curved inner face of the guard-arm of the draw-head B and in coöperation with the engagement of the outer end of the
- 10 link guard-arm with the coupler-head B prevents withdrawal of said link-coupler attachment from said coupler B notwithstanding the swinging attachment of said link-coupler with the head A. The parts referred to are made
- 15 with a sufficiently loose fit to allow the same to pass into and be released from interfitting or coupling connection when the knuckles are unlocked; but when said parts are coupled and the knuckles locked the release thereof can-
- 20 not occur by the lateral swinging of the attachment on its axis relatively to the coupler B, for the reason that such swinging of the attachment acts to force the projecting part c⁹ of said link into contact with the guard-arm
- 25 B², and the pressure between said parts will react to swing the outer end of the link guard-arm into contact with the opposing part of the coupler-head B. Thus the link is held loosely but reliably in interlocking connection with the coupler-head B.

The position of the parts preparatory to making a coupling is shown in Fig. 3, with the exception that the lock-pin C⁴ will be supported on the projection C⁵ of the tailpiece of the link-knuckle. Upon movement together of the parts in the act of coupling the knuckle B' strikes the tailpiece C³ of the link-knuckle and swings the latter inwardly into interlocking connection with said knuckle B'. When

35 40 the knuckle B' strikes the tailpiece of the link-knuckle and begins to swing the same inwardly, the forward end of the link has passed the extreme end of the guard-arm B² of the draw-head B such distance that said link cannot in the further closing movement of the parts be swung laterally out of coupling-line with the head B, as the guard-arms B² C² prevent the link swinging too far in one direction, and the engagement of the knuckles prevents the said link from swinging out of position in the other direction.

In the construction shown, Figs. 5 and 6, the knuckle of the coupler attachment is made rigid instead of being hinged, as in the

55 construction just described. As shown in said figures, D and E designate the two draw-heads, the latter having the usual swinging knuckle E' and guard-arm E². The emergency coupler attachment consists of a shank F, which is hinged at one end to the coupler-head D by a hinge-pin d, as is the attachment of the previously-described construction, and provided at its other end with a rigid laterally-directed knuckle or hook and between

60 65 its ends with a laterally-directed guard-arm

F², generally parallel with said knuckle. The space between the rigid knuckle and guard-arm receives the swinging knuckle of the draw-head E. The inner face of said guard-arm F² is provided with a rearwardly-curved recess f to permit the swinging knuckle to pass freely into and out of the space between said guard-arm and knuckle F' during the operation of coupling and uncoupling. The forward and laterally outer face of said attachment is provided with a projection f', which is adapted for engagement with the adjacent inner face of the guard-arm E², and said opposing parts coöperate with the outer end of the link guard-arm and adjacent part 70 75 80 of the coupler-head E to prevent the release of the intercoupled parts so long as the swinging knuckle E' of the head is locked closed, these parts coacting, as do the like parts of the previously-described construction, to prevent separation of the coupled parts. When the parts are separated and in position for coupling, (the swinging knuckle E' being at this time open,) the rigid knuckle of the attachment first strikes the tailpiece of said 85 90 95 swinging knuckle and begins to close the same, said knuckle entering the space between said rigid knuckle and the guard-arm F². From an inspection of the parts it will be observed that when the rigid knuckle is in position for engagement with the swinging knuckle-tailpiece it has passed inside the outer end of the guard-arm E² sufficiently far to prevent its being swung laterally out of coupling-line about its hinge-pin d, for any 100 105 tendency to lateral deflection toward the guard-arm E² will be arrested by contact of the extension f' of said attachment with the inner face of said guard-arm. If such lateral swinging of the attachment should occur, resulting in the contact of the extension f' thereof with the guard-arm, the coacting inclined faces of said parts will result in guiding the attachment into its proper coupling position with respect to the complete coupler. 110 Conveniently the strengthening-rib f² is hollowed to constitute a handle by which the attachment may be carried. The similar strengthening rib or ribs of the attachment first described may be likewise formed to provide such a handle.

In practice the locomotive of a train will be equipped with a number of the emergency coupler attachments described, and in the event of the breakage of the knuckles of one 115 or more of the couplers on a trip the attachments described are at hand to take the place of the disabled knuckles and constitute a connection which may be used in the same manner as an ordinary coupler to couple and uncouple the cars of the train. An advantage of the attachment described lies in the ease in which it may be applied to a disabled coupler and also in the fact that the coupling and uncoupling operations may be automatic. 120 125 130

ically accomplished thereby and without any unusual or hazardous movements or position on the part of the person doing the coupling. Another and important advantage arising 5 from the use of the attachment is that it may be employed with all standard couplers in use, and it therefore becomes universal in its application.

Changes may be made in the structural details without departing from the spirit of my invention, and I do not wish to be limited to such details except as hereinafter made the subject of specific claims, nor is the term "link" hereinbefore employed to designate 15 the attachment to be considered as a limiting term; but the part so designated may be made of any form most suitable for its application in each particular instance.

I claim as my invention—

20 1. In automatic car-couplers, an emergency coupling attachment designed to closely and interchangeably fit at one end in coupling engagement with all forms of the vertical-plane type of coupler having a rotative hook or knuckle and provided at its other end with an opening to receive a vertical pivot-pin by which it is adapted to be connected with another coupler, a coupling-knuckle or analogous coupling device.

25 2. In automatic car-couplers, an emergency coupler attachment designed to be hinged at one end to the draw-head in place of the usual swinging knuckle, and provided at its other end with a hook and with a guard-arm, the hook being adapted to closely and interchangeably fit and to be automatically coupled to all forms of the vertical type of coupler having a rotative hook or knuckle.

30 3. In automatic car-couplers, an emergency coupler attachment designed to be hinged at one end to the draw-head in place of the usual knuckle, and provided at its other end with a knuckle adapted to automatically intercouple with the rotating knuckle of 45 an adjacent coupler in a manner to retain the intercoupled draw-heads in substantial alinement with each other.

35 4. In automatic car-couplers, an emergency coupler attachment, designed to be hinged at one end to the draw-head in place of the usual knuckle, and provided at its other end with a rigid knuckle and in rear of said knuckle with a guide-arm, said rigid knuckle and guide-arm being adapted to automatically intercouple with the rotating knuckle of 55 an adjacent coupler in a manner to retain the draw-heads in substantial alinement with each other.

50 5. In automatic car-couplers an emergency coupler attachment designed to be loosely connected with the draw-head to swing laterally and provided at its outer end with a knuckle and in rear of said knuckle with a guard-arm, the inner face of said guard-arm

being provided with a rearwardly-curved 65 notch.

6. In automatic car-couplers an emergency coupler attachment designed to be loosely connected with the draw-head and provided at its outer end with a knuckle, said attachment being provided at its forward end with an extension adapted for contact with the guard-arm of an interlocking coupler to prevent said parts from uncoupling.

7. In automatic car-couplers, an emergency coupler attachment designed to be loosely connected with the draw-head and provided at its outer end with a knuckle and in rear of said knuckle with a guard-arm, said attachment being provided at its forward end with 80 an extension adapted for contact with the guard-arm of an interlocked coupler to prevent said parts from uncoupling.

8. In automatic car-couplers, an emergency coupling attachment designed to be 85 loosely connected with the draw-head and provided with a knuckle and in rear of said knuckle with a guard-arm, said guard-arm being provided on its inner face with a rearwardly-curved notch and the attachment being provided at its front end with a forward extension adapted for contact with the guard-arm of an intercoupled draw-head to prevent separation of said coupled parts.

9. In automatic car-couplers an emergency 95 coupling attachment designed to be loosely connected with the draw-head and provided with a knuckle and with a guard-arm, said guard-arm being formed to provide a handle by which the link may be carried.

10. In automatic car-couplers, an emergency coupling attachment designed to be loosely connected with the draw-head to swing freely laterally and provided with a knuckle designed to closely interlock with the 105 knuckle of an adjacent coupler, said attachment being provided with a thickened part having an inclined guide-surface which engages the guard-arm of said adjacent coupler and acting to prevent lateral separation of 110 said attachment and coupler so long as the knuckle of said coupler is locked closed.

11. An emergency car-coupler knuckle comprising a lug adapted to be pivoted between the ears of a coupler-head, a guard 115 member extending from the lug and forming with the knuckle-head a space to receive the head of the knuckle of a cooperating coupler, and a web extending between said lug and the rear surface of said guard member.

In testimony that I claim the foregoing as my invention I affix my signature, in presence of two witnesses, this 5th day of August, A. D. 1903.

JAMES A. HINSON.
